JEWELRY CASE

Ivy Coryne Davidson, Los Angeles, Calif.

Application January 9, 1951, Serial No. 13,719

Term of patent 14 years

(Cl. D80—5)

To all whom it may concern:

Be it known that I, Ivy Coryne Davidson, a citizen of the United States, residing at Los Angeles, in the county of Los Angeles and State of California, have invented a new, original, and ornamental Design for Jewelry Case, of which the following is a specification, reference being had to the accompanying drawing, forming part thereof.

Figure 1 is a perspective view of a jewelry case showing my new design, in a closed position;

I claim:

The ornamental design for a jewelry case, as shown.

IVY CORYNE DAVIDSON.
